(57) **CLAIM**

The ornamental design for a dish, glass and silverware handling cart, as shown and described.

DESCRIPTION

FIG. 1 is a top, left side, front isometric view of dish, glass and silverware handling cart showing the new design.

FIG. 2 is a left side end elevational view thereof.

FIG. 3 is a right side end elevational view thereof.

FIG. 4 is a top plan view thereof.

FIG. 5 is a front elevational view thereof.

FIG. 6 is a rear elevational view thereof.

FIG. 7 is a bottom plan view thereof.

FIG. 8 is a top, left side, and front isometric view of a second embodiment of the dish, glass and silverware handling cart;

FIG. 9 is a left side end elevational view of FIG. 8;

FIG. 10 is a right side end elevational view of FIG. 8;

FIG. 11 is a top, left side, and front isometric view of a third embodiment of the dish, glass and silverware handling cart;

FIG. 12 is a left side end elevational view of FIG. 11; and,

FIG. 13 is a right side end elevational view of FIG. 11.
